UNITED STATES PATENT OFFICE

ORIN M. BULLOCK, OF OAKLAND, CALIFORNIA, ASSIGNOR TO BULLOCK GARDEN TOOL COMPANY, A CORPORATION OF CALIFORNIA

GARDEN TOOL

Application filed January 13, 1925. Serial No. 2,070.

My invention is a garden tool of the mattock, pick, or the hoe type, in which a blade preferably of resilient metal is secured to the end of the handle by a U shaped bolt or clamp, the base of the clamp extending through the handle and the stems being positioned adjacent the handle and engaging the outside of the blade and clamping it in position.

10 My invention is particularly adapted for garden tools requiring a high quality of steel on account of their use and preferably formed on a curve with the concave side of the curve adjacent the end of the handle so that the clamping bolts press the blade tight against the end of the handle and the resiliency of the blade forms a tight connection which has a certain amount of give, or springiness.

20 My invention will be more readily understood from the following description and drawings in which:

Figure 1, is a side elevation of a mattock or pick illustrating the manner of clamping the blade to the handle and the use of wedges to change the inclination of the blade.

Figure 2 is an end view of the blade in the direction of the arrow 2 of Figure 1.

30 Figure 3 is an enlarged cross section on the line 3—3 of Figures 2 or 4 illustrating the clamping of a resilient blade by the U shaped clamp and the use of wedges to change the inclination of the blade.

35 Figure 4 is an enlarged section on the line 4—4 of Figures 1 or 3, illustrating the cross section of the blade, the wedges and the clamping bolt.

Figure 5 is a side view of a simplified construction in which the handle abuts directly against the blade and is held by the clamping bolts.

40 Figure 6 is a detail of one form of bolt which may be used to form the U shaped clamping bolt.

45 Referring particularly to Figures 1 to 4, the handle 1 may be of the usual type for the particular tool used and would be shaped in accordance with the practice for constructing handles for mattocks, picks, hoes,

or other different types of garden tools. The curved blade 2 is shown formed with opposite cutting edges 3 and 4 and if found desirable with upturned ribs 5 on each side of the central portion 6. The ribs 5 should be formed of such dimensions as to not seriously interfere with the flexing of the blade by means hereinafter set forth and described, or may be omitted in the interest of rendering the blade more flexible. A pair 60 of apertures 7 are provided in the blade spaced the proper distance apart to allow proper clamping as hereafter described.

The blade is attached to the handle by a U shaped clamp 9 which is formed of a rod 65 preferably having a base 10 and an upstanding stem 11, as shown in Figure 6. This rod is inserted through a bored hole 12 extending transversely across the handle from side to side and the straight end 13 is bent 70 parallel to the stem 11 as indicated in Figure 6. If desired a straight rod may be used and bent after being positioned through the handle. The upstanding stems 11 and 14 are inserted through the apertures 7 and 8 75 in the blade and clamped tight by nuts 15 on the screw threaded ends 16 of the U shaped clamp.

Wedges 17 and 18 forming a spacing member are inserted before the blade is attached to the end of the handle for the purpose of securing the blade to the handle at an angle thereto as clearly shown in Figures 1 and 3. It will be noted (see Fig. 3) that the wedges 17 and 18 have registering 80 apertures 19 passing therethrough which show a considerable marginal space surrounding stems 11 and 14 of the U-shaped clamp member 9 with the side walls of the apertures 19 of the wedge members 17 and 18 lying in the same plane in which position the wedge members 17 and 18 form a wedge having its inner face lying at right angles to the stems 11 and 14 and its opposite face tapering from left to right forming a wedge 95 tapered on one side only, the tapered side contacting at the ends thereof with the blade 2. Should it be desired to change the angle of the blade 2 with relation to the handle 1, the change of inclination of the blade 100

with relation to the handle may be readily accomplished by withdrawing nuts 15 from the stems 11 and 14, removing the blade and wedge member 18, then turning wedge member 18 end for end and re-placing it on the stems which will result in widening the composite wedge at one of its ends and lessening the width thereof at the other of its ends so that when the blade is re-placed upon stems 11 and 14 and the nuts 15 screwed home the blade will assume a position at approximately right angles to the handle 1. The marginal space provided in apertures 19 will provide for the angular position of the walls thereof resulting from the turning of wedge member 18 end for end.

10 In Figure 5 I show a simpler form of my implement in which the blades 3 are clamped direct to the squared end of the handle 23 without the intermediary wedges.

20 It will be readily understood that by the use of my construction blades may be used of very high quality steel, and using a minimum amount of such high grade metal.

25 There is no socket to be fitted onto a handle and the U shaped clamping bolt may be slightly tightened or loosened to change within small limits the curvature of the blades. Moreover, by the single expedient of inserting wedges or shifting wedges the blade can be tightened so as to suit tall or short persons for various types of work.

30 My invention is not to be confused with blades which are pivotally mounted on the end of a handle and secured in an adjustable position by wedges or by implements having sockets fitted on a handle with fastening wires attached to the implement and extended through the handle. My type of fastening for a blade to a handle may be utilized for many different types of tools and implements, especially such as have relatively thin blades of a high quality metal.

40 45 Having described my invention, what I claim is:—

50 A tool comprising in combination a handle, a transverse opening therethrough, a U-shaped clamping bolt having its base extending through said opening and its leg portions lying parallel to and along the sides of said handle, the ends of said legs being threaded and extending a substantial distance beyond the end of the handle, an

55 apertured concave tool blade fitted over the extending ends of said U-bolt legs, nuts threaded on the ends of said U-bolt legs for clamping said blade in position and means at the end of said handle against

60 which said blade is clamped, said means projecting laterally beyond said U-bolt legs and adapted to contact with said blade at points more remotely spaced than said U-bolt legs.

ORIN M. BULLOCK.
